UNITED STATES PATENT OFFICE.

B WICKLIFFE TWYMAN, OF MARYSVILLE, MICHIGAN.

AUTOMOBILE JACK.

Application filed May 11, 1925. Serial No. 29,297.

My invention relates to improvements in automobile jacks and is primarily directed toward a jack for use with automobiles having the so-called "balloon" tires. Automobiles equipped with this type of tire require a jack having a long lift and which may be lowered to a point where the engaging portion of the jack is not much more than four or four and a half inches from the ground. At the same time a long lift is necessary on the part of the jack to clear the wheel from the ground in event the tire becomes deflated.

My invention is directed toward this type of jack wherein I provide an extremely long lift and wherein the engaging member of the jack may be lowered to a point very close to the ground.

For the purpose of disclosing my invention I have illustrated certain embodiments thereof in the accompanying drawings in which—

Fig. 1 is a side elevation of a jack embodying my invention;

Fig. 2 is an end elevation thereof;

Fig. 3 is a plan thereof;

Fig. 4 is a detail side elevation with one of the yoke plates removed to show more clearly the manipulating mechanism;

Fig. 5 is a sectional view taken on the line 5—5 of Fig. 1;

Fig. 6 is an elevation of a modified form of disengaging the manipulating dogs.

In the embodiment of the invention illustrated I provide a pair of oppositely disposed toggles each comprising the top links 1, 1 and the bottom links 2, 2. The top links are pivotally connected at their upper extremities by a pair of top link plates 3, 3 which are spaced apart to receive the ends of the links and provided with pivots 4, 4 for pivotally connecting the toggle links 1, 1 and the top links 3, 3 together. These top links 3, 3 are spread intermediate of their ends as at 5 to receive the shank 6 of the usual engaging member 7, the shank being rotatably supported in the spread portion.

The lower ends of the two bottom toggle links 2, 2 are pivoted by means of pivot pins 8, 8 between the vertical members 9 of a pair of angle plates 10, the horizontal portion of these plates forming the base of the jack and to give stability I secure on the bottom face of the angle plates 10 a foot plate 11 which also provides a means for maintaining the angle plates in position. The ends of the

horizontal members of the angle plates 10 are bent downwardly to form flanges 12 the bottoms of which lie in the same horizontal plane as the bottom of the plate 11. The knuckle ends of one set of toggle links 1 and 2 are connected together by a pair of yoke links 13 straddling the toggle links and provided with pivot pins 14, 14. The opposite pair of toggle links 1 and 2 are connected together by a pair of yoke plates 15 which are spaced apart to receive between the same the knuckle ends of the toggle links 1 and 2, which ends are connected by pivots 16, 16 to the yoke plates.

For manipulating the knuckles of the oppositely disposed toggle links to cause them to approach one another and thereby straighten the toggles for lifting the jack or for permitting them to separate and bend the knuckles to thereby lower the jack, I provide a rack bar 17 pivotally connected by the pivot pin 18 to the yoke links 13 and slidably mounted between the yoke plates 15. An oscillating pawl bar 19 is pivoted on one of the yoke plates 15 and its pivot stud 20 extends through the yoke plate being squared on its outer end for the reception of a squared socket of a manipulating handle 21. This pawl bar 19 is provided with a pawl 22 adapted, during the oscillation of the bar, to engage the rack of the rack bar 17 and draw the two knuckles of the toggles together. A holding pawl 23 is also mounted on one of the yoke plates to engage the rack of the rack bar 17 during the retracting movement of the pawl 22.

Hanging from suitable transversely extending pins 24, 24 extending between the yoke plates 15 is a brake shoe 25, this shoe being provided with diagonally disposed elongated slots 26 through which the supporting pins 24 pass and intermediate of its ends with an arcuate slot 27 in which operates a pin 28 on an extension 29 of the pawl arm 19. This brake shoe is provided with a pair of upwardly extending arms 30 and 31 adapted when the plate is raised or moved vertically, to engage the pawls 22 and 23 and raise the same out of operative relation with respect to the rack of the rack bar 17. In normal operation, that is, the operation of raising the jack, the oscillating movement of the pawl bar 17 is limited by a stop pin 32 so that the oscillation of the pin 28 will be within the limits of the slot 27. In event it is desired to lower the jack the stop pin 32

may be withdrawn from the path of the handle 21 by manipulating the cam lever 33 and this will permit an extreme throw of the lever to the left, viewing the structure in 5 Fig. 1, which will cause the pin 28 to engage the wall of the slot 27 and raise the brake shoe 25 into frictional engagement with the lower edge of the rack bar 17, at the same time moving the arms 30 and 31 into engagement with the pawls 22 and 23 and disengaging them from the rack. Due to the leverage obtained on the operating arm 21, sufficient braking friction may be obtained 10 on the lower edge of the rack bar 17 by the 15 brake shoe 25 to hold the toggles from separating under the influence of any weight applied to the top thereof. However, by slightly easing up on the arm 21 the brake may be released to any extent desired to permit 20 the weight on the top of the toggles to bend the same, thereby lowering the jack. During this manipulation however, the arms 30 and 31 will remain in engagement with the pawls 22 and 23 to prevent them from 25 dropping into engagement with the rack of the rack bar 17.

In Fig. 6 I have illustrated a structure wherein, if desired, the pawls 22 and 23 may be disengaged from the rack bar without 30 the manipulation of the brake shoe 25 or of the lever 21. In this structure the pawl bar 19 is extended as at 34 and carries a bell crank lever 35 pivoted at 36 thereto. This lever is connected to a cross bar 37 in turn 35 connected to each of the pawls 22 and 23 and the lever 35 under the influence of the spring 38 tends to force the pawls 22 and 23 into engagement with rack. In event it is 40 desired to disengage the pawls the lever 35 may be manipulated to raise the arm 37 which in turn will raise the pawls. It will be noted in this construction that pawls 22

and 23 are positively moved into engagement with the rack instead of being allowed to be moved into engagement therewith under the 45 influence of gravity.

I claim as my invention:

1. In an automobile jack, the combination with a pair of oppositely disposed toggles, of a rack bar connected to one of said toggles, a pawl connected to the other of said toggles, adapted to engage said rack bar and means oscillating said pawl for moving said rack bar to draw the knuckles of the toggles together to thereby raise the jack. 50

2. In an automobile jack the combination with a pair of oppositely disposed toggles connected together at their opposite ends, of a rack bar connected to the knuckle of one of said toggles, an oscillating pawl connected to the knuckle of the opposite toggle, means for oscillating said pawl into engagement with said rack for moving the knuckles of said toggles toward one another and a holding pawl connected with the knuckle of one 60 of said toggles for engaging said rack. 65

3. In an automobile jack the combination with a pair of oppositely disposed toggles connected together at their opposite ends, of a rack connected to the knuckle of one of 70 said toggles, a holding pawl and an oscillating pawl connected to the knuckle of the opposite toggle and normally in engagement with said rack, means for operating said oscillating pawl means for disengaging said pawl from said racks and a brake shoe arranged to be moved into engagement with 75 said rack for holding the same when said pawls are disengaged.

In witness whereof I, B WICKLIFFE TWYMAN have hereunto set my hand at Indianapolis, Indiana, this 9th day of May, A. D. one thousand nine hundred and twenty-five. 80

B WICKLIFFE TWYMAN.
